(57) **CLAIM**

The ornamental design for an architectural mesh, as shown and described.

DESCRIPTION

FIG. 1 is a plan view of an architectural mesh showing the design.

FIG. 2 is a side view of an architectural mesh showing the design.

FIG. 3 is a cross-sectional view of one of the strands that make up an architectural mesh showing the design; and,

FIG. 4 is a top perspective view of an architectural mesh showing the design.

The architectural mesh has an indeterminate length and width and the pattern as shown repeats uniformly throughout its length and width.
